DESIGN FOR AN ELECTRICAL RAZOR

Tomlinson I. Moseley, San Francisco, Calif., assignor to Motoshaver, Inc., Los Angeles, Calif., a corporation of California

Application January 2, 1937, Serial No. 66,863

Term of patent 14 years

To all whom it may concern:

Be it known that I, Tomlinson I. Moseley, a citizen of the United States and resident of the city and county of San Francisco, State of California, have invented a new, original, and ornamental Design for an Electrical Razor, of which the following is a specification, reference being had to the accompanying drawing, forming part thereof.

Referring to the drawing:

Fig. 1 is a front elevational view of an electrical razor, showing my new design;

Fig. 2 is a side elevational view thereof; and

Fig. 3 is a view looking towards the rear face

of the electrical razor as shown in Fig. 1.

I claim:

The ornamental design for an electrical razor substantially as shown.

TOMLINSON I. MOSELEY.
